A. H. DE VOE,
TAPE CONTROLLING DEVICE,
APPLICATION FILED JULY 16, 1917.

1,267,520.

Patented May 28, 1918.

UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

TAPE-CONTROLLING DEVICE.

1,267,520.

Specification of Letters Patent.

Patented May 28, 1918.

Application filed July 16, 1917. Serial No. 180,753.

To all whom it may concern:

Be it known that I, ALBERT H. DE VOE, a citizen of the United States, residing at Westfield, in the county of Union and State 5 of New Jersey, have invented certain new and useful Improvements in Tape-Controlling Devices, of which the following is a specification; reference being had therein to the accompanying drawings.

10 This invention relates to a tape controlling device for use in conjunction with sewing machines.

In applying knit bindings especially bias cut bindings to the edge of body-fabrics it is 15 desirable to maintain a uniform tension of a small amount on the binding and to prevent the edges of the binding from curling or roping during the application of the binding to the fabric. It is the object of this 20 invention to provide a tape or binding controlling device for maintaining the binding flat and applying a uniform tension on the binding as it unwinds from a roll.

Briefly the construction comprises an axial 25 supporting pin for tape wound in the form of a roll and carried by hinged arms which are so arranged that the periphery of the roll is constantly held in contact with the receiving end of a strip-guide which is movable with one of the arms and with an abutment fixed to the frame, the idea being to let the size of the roll of tape as it diminishes 30 control the tension on the tape and to make the roll of tape move up to the receiving end of the strip-guide so as not to allow the edges of the strip to curl.

In the accompanying drawings Figure 1 is a side elevation of the machine and Fig. 2 a plan view with the invention shown applied thereto in working relation.

The tape controlling device is shown as it appears applied to a chain-stitch machine but it will be manifest the character of the stitch-forming mechanism may be varied as 45 desired.

Sunk below the upper surface of the cloth-plate 1 is a binder 2 of well known form having edge folding portions 3 and a curved fan-tailed receiving portion 4 crossed by a 50 retaining strap 5. The binder is supported

in any suitable manner with its longitudinal axis substantially parallel to the line of feed being inclined only slightly downward from its receiving to its delivery end.

From the receiving end of the binder 2 a 55 strip-guide 6 extends in the direction of the length of the machine to a point remote from the needles where its receiving end is located well out of the operative's way. The strip-guide 6 is set on edge, that is, its flat 60 tubular body lies in a substantially vertical plane at right angles to the cloth-plate. Intermediate the ends of the strip-guide and below the threading slot 7 therein is soldered or otherwise suitably fixed a clip angle 8 65 slotted at 9 to permit of adjustably securing the strip-guide to an arm 10. Adjacent the receiving end of the binder 2 the arm 10 has ears 11 pierced to receive the vertically extending pivot pin 12 fixedly secured in any 70 suitable manner in a bracket 13 which is adjustably secured by a stud-screw 14 and a slot and screw connection 15 to the front apron 16 of the cloth-plate 1.

To the free end of arm 10 a second arm 75 16, conveniently termed a forearm, is pivoted as clearly shown at 17. The forearm 16 is shorter than the main arm 10 and at its free end in a socket 18 removably carries the vertically extending pin 19 and flange 20 80 axially supporting a roll of tape or binding 21.

Fixed to the machine frame in any suitable manner as by screws 22 is an abutment 23 having a face, preferably but not necessarily flat, against which the periphery of the roll of tape tangentially bears whatever 85 may be the size of the roll.

The receiving end 24 of the strip-guide is defined by rolled or rounded edges facilitating passage of the strip into the guide especially when the strip is cut on the bias and consequently easily distended.

Springs 25 are coiled around the pivots 12 and 17 respectively with one end bearing 95 on the main arm 10 and the other end fitted in the collars 26 fixedly but adjustably secured by the screws 27 to the pivot pins. These springs 25 normally move the free ends of the main arm and forearm in inter- 100

secting arcs and cause the axial supporting pin 19 for the tape-roll to move in a path between and diagonally of the face of the abutment 23 and of the path of the receiving end 24 of the strip guide.

From the foregoing description taken in conjunction with the drawings it will be apparent that the springs 25 will urge the arms in such wise that the tape will be maintained 10 constantly in contact with the receiving end of the strip-guide and also with the abutment thereby keeping the edges of the tape from curling. It will also be obvious that the coiled springs 25 exert a decreasing force 15 and consequently allow the tape to unwind against less friction as the size of the roll decreases and consequently demands greater pull to unwind the tape. The decreasing friction compensates for the decreasing mechanical advantage of unwinding and a substantially uniform tension is placed upon the tape or binding at all times.

The adjustment afforded by the slot and screws 14 and 15 of the bracket 13 permits 25 of locating the axis of the strip-guide in alignment with the axis of the binder so that the small tension which is uniformly placed upon the tape will be equally applied to the edges of the tape.

Having thus set forth the nature of the invention, what I claim herein is:—

1. In a device for controlling tape as it is supplied to sewing machines, in combination, a strip-guide, an abutment to one 35 side of said strip-guide, a tape-roll, a tape-roll support movably controlled by the size of the tape-roll to maintain the periphery of the roll in contact with the receiving end of said strip-guide and with the abutment 40 whereby the edges of the tape are prevented from curling.

2. In a device for controlling tape as it is supplied to sewing machines, in combination, a strip-guide pivoted at its delivery end 45 and free to move in a circular path at its receiving end, an abutment to one side of the delivery end of the strip-guide, a tape-roll, a tape-roll support and means for moving the support carrying the tape-roll diagonally in a path between the abutment and the circular path of movement of the delivery end of the strip-guide whereby a substantially constant tension may be applied to the tape.

3. A device for controlling tape as it is supplied to sewing machines, in combination, an abutment, a binder, a strip-guide pivoted at its delivery end adjacent the receiving end of said binder with its free end 55 movable toward and from the abutment, a roll of tape, an axial support for said roll of tape, an arm carrying said axial support and movably connected to the pivoted strip-guide, and means controlled by the size of the roll of tape for maintaining the periph-

ery of the roll in contact with the receiving end of the strip-guide and with the abutment as the roll unwinds.

4. In a device for controlling tape as it is supplied to sewing machines, in combination, a binder, a strip-guide, an abutment, a roll of tape, an axial support for said roll of tape, a forearm carrying said axial support, a pivoted main arm supporting said strip-guide and forearm, said forearm being 75 articulated to said main arm and resilient means for moving said main and forearms as the roll of tape unwinds whereby its periphery may be held constantly in contact with the abutment and with the receiving end of the strip-guide.

5. In a sewing machine, in combination, a binder having its longitudinal axis arranged substantially parallel to the line of feed, a strip-guide having its longitudinal axis disposed at an angle to the line of feed, a vertically extending pivot for said strip-guide adjacent its delivery end, an arm pivotally connected to said strip-guide and carrying a support for a roll of tape, a spring 90 for urging said arm bodily toward said abutment, and a second spring for simultaneously urging said support on the arm bodily toward the receiving end of the strip-guide.

6. In a sewing machine, in combination, a binder, a strip-guide, an abutment, a tape-roll, a tape-roll support movably controlled by the tape-roll to maintain the periphery of the tape-roll in contact with the abutment and with the receiving end of the strip-guide, said means including a common supporting arm, a vertically arranged pivot for one end of said arm and means for tilting the pivot for said arm in a vertical plane 105 whereby the axes of the binder and of the strip-guide may be arranged to intersect.

7. In a sewing machine, in combination, a binder, a strip-guide, a fixed abutment, a tape-roll, an axial support for said tape-roll, 110 means for moving said axial support to maintain the periphery of the tape-roll constantly in contact with the abutment and with the receiving end of said strip-guide, said means including a pivoted bracket 115 carrying said strip-guide and said axial support, and means for adjusting said strip-guide on said bracket in a plane at right angles to the axial support for the roll of tape.

8. A device for controlling tape as it is supplied to sewing machines, in combination, a strip-guide, an abutment to one side of said strip-guide, a tape-roll, a tape-roll support, and means for maintaining the periphery of the tape-roll in contact with the receiving end of said strip-guide and with the abutment whereby the edges of a tape are prevented from curling.

9. In a device for controlling bias cut 130

knit binding as it is supplied to sewing machines, in combination, a binder having a U-shaped folding portion, a roll of tape, a tape-roll support, an abutment having a face 5 which is straight in vertical directions and of a vertical length at least equal to the width of the widest binding to be handled, means between said U-shaped folding portion of the binder and the tape-roll for maintain-

ing the binding flat, and means controlled 10 by the size of the roll for maintaining the roll in contact with the face of the abutment whereby tension may be applied uniformly over the surface of the binding.

In testimony whereof, I have signed my 15 name to this specification.

ALBERT H. DE VOE.
